WINDOW SASH AND FRAME

Martin H. Munson, Red Wing, Minn.

Application August 20, 1935, Serial No. 37,085

1 Claim. (Cl. 20—42)

This invention relates to window sashes and frames and has for an object to provide screen sashes and storm sashes which are selectively foldable and slideable into storage compartments built into the window frame, the pivots being disposed intermediate the ends of the sash elements in contrast to being disposed at the line of juncture of the elements, whereby a more balanced arrangement will be produced and jamming or sticking of the sash elements positively prevented.

A further object is to provide a device of this character in which the sash elements in folded relation lie one against the other transversely to 15 or at a right angle to the track in which the pivots are carried so as to be stored in minimum space and whereby the sash elements may be passed edge on into the storage compartments at the sides of the window frame to be quickly 20 stored or quickly moved to operative position.

A further object is to provide a device of this character in which the screen sashes and storm sashes may be operated from inside the room, the window pane sashes for this purpose being folded 25 in the same manner as the screen and storm sashes to permit access to the latter.

A further object is to provide a device of this character which will be formed of a few strong, durable and inexpensive parts, which may be 30 manufactured at minimum expense, and which will not easily get out of order.

With the above and other objects in view the invention consists of certain novel details of construction and combinations of parts hereinafter 35 fully described and claimed, it being understood that various modifications may be resorted to within the scope of the appended claim without departing from the spirit or sacrificing any of the advantages of the invention.

40 In the accompanying drawings forming part of this specification,

Figure 1 is a front elevation of the improved window frame and sash construction looking from inside the building.

45 Figure 2 is a cross sectional view taken on the line 2—2 of Figure 1 showing the hinges which connect the folding elements of the screen sashes.

Figure 3 is a cross sectional view taken on the 50 line 3—3 of Figure 1 showing the folding elements of the window sashes.

Figure 4 is a cross sectional view taken on the line 4—4 of Figure 1 with the window sashes in partly folded position to permit access to the screen sashes, and showing the storm sashes 55 stored in one of the storage compartments.

Figure 5 is a vertical sectional view taken on the line 5—5 of Figure 1, showing the tracks and pivots for the sashes at the top of the window frame, and

Figure 6 is a vertical sectional view taken on the line 6—6 of Figure 1 showing the tracks and pivots for the sashes at the bottom of the window frame.

Referring now to the drawings in which like characters of reference designate similar parts in the various views, 10 designates the uprights of a window frame, each being open on the inner side and closed by a hinged door 11 to provide a storage compartment, as best shown in Figure 4. The head 12 and the sill 13 of the window frame are provided with tracks 14 and 15 respectively, each track being preferably a metal tube of rectangular cross section having a slot 16 to receive the pivots of the folding elements of the screen and storm sashes hereinafter described. Likewise, the head and sill are provided with similar tracks 17 and 18 having slots 19 to receive the pivots of the window sashes as will presently be described.

The screen sash elements 20 are hinged together at their longitudinal edges by double swinging hinges 21 of the three leaf type, best shown in Figure 2, and midway between the edges of each sash element pivots 22 and 23 slidably connect the sash elements to the upper and lower tracks 14 and 15, as best shown in Figures 5 and 6. By referring to Figure 4 it will be seen that the end portions of the track are offset obliquely as shown at 24 to dispose the extreme end portions 25 of the track at the center of the corresponding storage compartment. The purpose is to permit the screen sash elements to be slid into or out of the storage compartment on one side of the window frame and folded to lie flat against each other at a right angle to the tracks at the top and the bottom of the compartment whereby the screen sash elements occupy minimum space when stored and at the same time may be easily collapsed into the compartment or slid out of the compartment to extended position and during such sliding movement because of the pivots being positioned midway between the edges of the sash elements the sash elements will be nicely balanced to prevent jamming.

The storm sash is formed of elements 26 hinged together as just described to fold flat upon each other and be compactly stored in the storage compartment at the right of the window frame as shown in Figure 4. The storm

sash elements may be formed simply of boards or may be equipped with panes, but in either event when the screen sashes are collapsed into the screen storage compartment the storm sash elements 5 may be slid out of the storm sash storage compartment to operative position as will be understood. The storm sash elements are provided with double swinging hinges 27 of the three leaf type and are pivoted centrally between the 10 longitudinal edges to the tracks by pivot pins 28.

To permit access to either the screen sashes or the storm sashes from inside the building the window sash elements 29 are hingedly connected together by the double swinging hinges 30 of the 15 three leaf type and are pivotally and slidably mounted upon the upper and lower tracks 17 and 18 by means of pivots 31 and 32, as best shown in Figures 5 and 6. The pivots are arranged midway between the edges of each sash element so 20 that the elements are nicely balanced and jamming eliminated.

In operation assuming that the screen sashes are in use and it is desired to substitute the storm sashes, for example, the window sashes 29 may 25 be folded to incline at acute angles to each other, as best shown in Figure 4, whereupon the door 11 of the screen storage compartment may be rocked open and the screen sash elements may then be slid along the tracks and folded to lie flat 30 against each other in the storage compartment.

The door 11 may now be closed. The door of the storm sash storage compartment may now be opened and the storm sash elements slid out of the compartment along the tracks to the position previously occupied by the screen sash elements. To store the storm sash elements and move the screen sash elements to operative position the above procedure is reversed. 5

From the above description it is thought that the construction and operation of the invention 10 will be fully understood without further explanation.

What is claimed is:

The combination with a window frame, of a pair of tracks on the top of the frame, a pair of 15 tracks on the bottom of the frame, a storage compartment on the side of the frame between said tracks, sash elements hingedly connected together at the vertical edges and pivoted at the centers of the upper and lower edges to one pair of the 20 tracks, said sash elements being foldable flat upon each other for storage in said compartment, and window sash elements pivotally connected together at the vertical edges and pivotally connected at the centers of the upper and lower 25 edges to the other pair of tracks for folding upon each other to permit access to the first named sashes.

MARTIN H. MUNSON. 30
